UNITED STATES PATENT OFFICE.

WALTER E. HODGDON, OF PORTLAND, MAINE.

FAUCET.

1,082,329.

Specification of Letters Patent.

Patented Dec. 23, 1913.

Application filed August 15, 1912. Serial No. 715,145.

To all whom it may concern:

Be it known that I, WALTER E. HODGDON, a citizen of the United States, residing at Portland, in the county of Cumberland and State of Maine, have invented certain new and useful Improvements in Faucets, of which the following is a specification.

In dispensing certain liquids, root beer, for example, it is desirable to draw the major part from a still liquid and a smaller portion from a live liquid, or a liquid under high pressure, the two being properly intermingled while being dispensed.

The object of the present invention is to provide a faucet adapted to accomplish the above result in a satisfactory manner.

In the drawing herewith accompanying and forming a part of this application, Figure 1 is a vertical sectional view partly in elevation of my improved faucet; Fig. 2 is a plan view of the packing between the stem flange and the top of the casing; and Fig. 3 is a top plan view of the rotatable valve.

Same reference characters indicate like parts in the several figures.

In said drawing, A is a valve casing provided with an upwardly tapering valve chamber B extending into the casing from the bottom. Mounted in said chamber is a hollow, rotatable, tapering valve C adapted to fit closely the walls of said chamber. Extending horizontally through the casing is an inlet port D and through the vertical wall of the valve is a port D', which ports 35 may register or non-register according as the valve is turned. Mounted in the casing is a valve operating stem E provided with a laterally extending flange E' adapted to fit closely in a recess F in the top of the casing 40 and with a projection E² the end of which is angular in cross section and adapted to project downwardly through an angular opening G in the top of valve C. The valve casing is provided with a second inlet port 45 H which may be of smaller capacity than inlet port D, said port H extending for a short distance horizontally, thence vertically into recess F and through a packing I interposed between the top of the valve casing 50 and the flange of the valve stem, thence horizontally a short distance into said flange, thence horizontally to the center of the stem, and thence downwardly to the end of the stem to discharge into chamber C in the 55 valve. The stem is held in place in any convenient manner, preferably by a nut J hav-

ing threaded engagement with the casing and a supplemental nut K having threaded engagement with nut J. The lower end of the casing is provided with a nozzle L, and interposed between the nozzle and the valve is a coil spring N.

The operation of my improved device is as follows: When the valve and its operative stem is in the position shown in Fig. 1, the still liquid flows through port D in the casing and port D' in the valve. At the same time the live liquid flows freely through port H in the casing, the port H' in the packing and the port H² in the stem, and is discharged into the valve chamber at a right angle to the still liquid entering the chamber through port D, thereby becoming thoroughly intermingled before being discharged through the nozzle. To shut off the discharge, the stem is turned by means of a lever O, a slight turning moving the valve and the flange of the valve stem so as to bring the port D' out of register with the port D and the port H² out of register with the ports H' and H.

The advantages of my improved faucet are that it is simple in construction and operation; the liquid under pressure entering the valve chamber through the top of the valve has no tendency to force the valve away from its seat when the inlet port H² is open, obviating the danger of leakage, and the liquid is thoroughly mixed in the valve chamber while being dispensed.

Having thus described my invention and its use, I claim:

1. In a faucet, a valve casing, a vertical, rotary, hollow valve mounted in said casing, a valve stem mounted in said casing and provided with a horizontal flange, the lower extremity of the stem extending through the top of the valve, an inlet port extending through the casing and valve horizontally, and a second inlet port extending into the casing, thence vertically into said flange and thence through the flange to the stem and thence through the stem to the valve chamber, the streams entering through said ports intersecting in the open chamber at right angles to each other, the point of intersection being below the delivery end of the vertical inlet port, whereby rotation of the valve and stem simultaneously opens or closes both of said ports.

2. In a faucet, a valve casing provided with a circular recess in the top thereof, a

2

vertical, rotary, hollow valve mounted in said casing, a valve operating stem mounted in said casing and provided with a circular flange adapted to fit in said recess, the lower end of the stem projecting through the top of the valve, a packing interposed between the casing and the flange, an inlet port extending through the casing and valve horizontally, and a second inlet port extending 10 into the casing, thence vertically through the packing and into said flange and thence through the flange to the stem and thence

through the stem to the valve chamber, the streams entering through said ports intersecting in the open chamber at right angles 15 to each other, the point of intersection being below the delivery end of the vertical inlet port, whereby rotation of the valve and stem simultaneously opens or closes both of said ports.

WALTER E. HODGDON.
